UNITED STATES PATENT OFFICE.

CHARLES F. DUTTON, JR., OF CLEVELAND, OHIO.

PROJECTION-LANTERN.

No. 887,928.

Specification of Letters Patent.

Patented May 19, 1908.

Application filed March 6, 1905. Serial No. 248,422.

To all whom it may concern:

Be it known that I, CHARLES F. DUTTON, Jr., a citizen of the United States, residing at Cleveland, in the county of Cuyahoga and State of Ohio, have invented certain new and useful Improvements in Projection-Lanterns, and do declare that the following is a full, clear, and exact description of the invention, which will enable others skilled in the art to 10 which it appertains to make and use the same.

My invention relates to improvements in projection lanterns and the improvement consists in the construction and combination of parts substantially as herein shown and more particularly pointed out in the claims.

One of the objects of my improvement is embodied in the means for detachably and 20 yieldingly supporting each condensing lens within the lantern body or cylinder.

Another object is embraced in the mounting for the slide carrier and the front condenser lens and whereby said carrier may be 25 rotated in a plane at right angles to the optical axis and adapting both carrier and lens to be removed together from the lantern body.

A further object is provided for in the construction of the base board and the slidable supports for the objective lens mounting and for the lantern body and whereby adjustment and locking of said parts is readily obtained and fixed.

40 Further objects are also embodied in the construction of the base board and provision therein for the movement of the arc light carbons, and also in the means for supporting other slides and objects upon the slide carrier.

In the accompanying drawings Figure 1 is a central longitudinal sectional view of my improved lantern with the objective lens mounting in side elevation. Fig. 2 is a cross 45 section on line y, y , Fig. 1 looking to the rear and showing the slide carrier rotatably mounted upon the main lantern body. Fig. 3 is a sectional view of the slide carrier and its support with the lens removed and at one 50 side. Fig. 4 is a cross section of the lantern body at x, x , Fig. 1 looking to the front, and Fig. 5 is a perspective view of the sliding lamp or objective lens support showing the friction spring thereon.

55 The main body of the lantern comprises a metallic cylinder A open at its ends and sup-

ported by legs 2 secured to base board B. A bed plate C is adapted to slide upon base board B and to this end said board B is grooved and undercut at 3 its full length at 60 each side and bed plate C has a rabbeted edge 4 at one side and also a bow shaped spring 5 at its opposite side engaged in the opposite under-cut portions 3. Spring 5 serves to lock and hold plate C in any adjusted position and also takes up all wear as well as to provide for freedom of movement of the plate regardless of shrinkage of the wood.

An electric arc light D or other suitable lighting apparatus is mounted upon slide 70 bed plate C. As shown, carbons 6 and 7 are supported by adjustable brackets 9 and 8, respectively, which are jointly actuated and operated by hand screw 10 geared to vertical screw 11. A screen or plate 12 screens the 75 light at the rear of the lantern. Cylinder A is slotted or open at its bottom at 13 to permit forward or backward movement of the lighting apparatus within cylinder A, and base board B is also slotted at 14 to provide 80 for free movement of carbon 6. Cylinder A is also open at its top, a portion being cut away and side walls 14 at each side bent back and perforated to provide an open support for a roof or cover 15 which is preferably lined upon its inside with asbestos or like material a. The main portion of the heat generated by the lighting apparatus is thus permitted to escape at the top of the cylinder although other openings also permit 85 egress of the heat.

A pair of condensing lenses E and F, respectively, are located at the front and within the end of cylinder A and are separately supported and also removable from their respective supports. Thus, lens E is held in place by a set of spring clips 16, three in number arranged and riveted at equal distances apart and within and upon cylinder A and said lens is of less diameter than the inner 100 diameter of cylinder A thereby leaving a free space all around the lens for the circulation of air which enters through the circular row of openings 17 in the wall of the cylinder. Clips 16 have angularly bent free ends to engage and hold the edge of the lens and are adapted to spring back to permit the lens to be removed. The spring support obtained by this arrangement permits lens E to be removed at any time and allows for all expansion and contraction of the lens and body A 105 without in any wise endangering the lens or

altering its position centrally within the cylinder. Lens F is likewise supported by means of like spring clip members 18 but in this case, said members and lens F are made a part of a removable end cap or thimble 19 which is adapted to fit snugly within the open end of cylinder A and is held in locked relation thereto by means of spring clamps 20 on cylinder body A. Although clamps 20 hold thimble 19 in place, nevertheless said thimble is removable and is also rotatable in its seat to permit a rotary adjustment of slide carrier G which is mounted upon the front face of the thimble. Thus, carrier G is removable with thimble 19, and lens F is also removable with both and also independently removable from the thimble. It often occurs that pictures are mounted improperly upon the slides and to the end that a true horizon line be obtained from such pictures, I find a rotary adjustable slide carrier of great advantage to bring the pictures true and even. Slide carrier G is slotted lengthwise and carries the slides 21 for the plates of a given size as usual. If I wish to use a larger sized slide carrier or other slides or objects too large to fit carrier G, I mount the same at the front of carrier G and to this end provide projecting pins 22 upon which the same may rest. At the front of cylinder A and axially in line therewith is the objective lens mounting H having a cylindrical hood 23 attached thereto and projecting toward the rear. A slideable support 24 for mounting H and hood 23 is mounted and adapted to slide back and forth upon base board B in the same manner as bed plate C, and is adapted to be shifted to bring the objective lenses and condensing lenses in the right relation.

What I claim is:

1. In a projection lantern, a cylindrical lantern body and a condensing lens removably mounted therein apart from said body about its edge, and said body having openings opposite said lens, in combination with a cap removably mounted on said body and a detachable lens therein apart from the wall thereof.
2. In a projection lantern, a cylindrical

body and an inner lens mounted therein, a slide carrier and a rotatable support therefor mounted upon said body, an outer lens within said support, and spring clips to engage and hold said outer lens.

55

3. In a projection lantern, a cylindrical lantern body, a series of spring clips mounted within said body at its front end, a condensing lens removably supported upon said clips, a slide carrier and a support therefor rotatably mounted and detachably secured upon said lantern body, spring clips within said support, and a condensing lens removably mounted upon said clips.

60

4. In a projection lantern, a cylindrical lantern body, a set of condensing lenses mounted within one end of said body, a slide carrier supported at the front of said lenses, and forwardly projecting pins upon said slide carrier adapted to support larger slides or other objects.

65

5. In a projection lantern, a lantern body and condensing lenses therefor, a supporting base for said body, a grooved and rabbeted portion lengthwise of said base, a slideable plate having a rabbeted edge at one side and a spring upon the other side adapted to fit within said rabbeted portion of said base, and a lighting device supported upon said slideable plate, in combination with an objective lens mounting at the front of said lantern body and axially in line therewith.

75

6. In a projection lantern, a cylindrical lantern body having an open top and an asbestos lined cover above the same and provided with a slot lengthwise of its bottom, condensing lenses mounted within said body at its front end, a supporting base for said body, an electric arc light apparatus and a slideable base therefor mounted upon said base, a slot lengthwise of said base, an objective lens mounting at the front of said body, and a slideable support for said objective lens mounting.

80

In testimony whereof I sign this specification in the presence of two witnesses.

CHARLES F. DUTTON, JR.
